TOWNHOUSE COMPLEX

George D. Fonville, Dearborn, Mich., assignor to Kaufman & Broad Homes, Inc., Southfield, Mich., a corporation of Michigan

Filed Aug. 11, 1965, Ser. No. 86,542

Term of patent 14 years

(Cl. D13—1)

FIG. 1

FIG. 2

FIG. 2 is a fragmentary end elevational view;
FIG. 3 is a fragmentary front elevational view.

The rear portions not shown are plain.

Portions of the roof not shown are the same symmetrically as corresponding adjacent portions which are shown.

I claim:

The ornamental design for a townhouse complex, substantially as shown and described.
